UNITED STATES PATENT OFFICE.

JOHN BERG, OF CHICAGO, ILLINOIS, ASSIGNOR TO LLOYD W. GOLDER,
OF CHICAGO, ILLINOIS.

BLOWPIPE APPARATUS.

No. 839,540.

Specification of Letters Patent.

Patented Dec. 25, 1906.

Application filed October 27, 1904. Serial No. 230,269.

To all whom it may concern:

Be it known that I, JOHN BERG, a citizen of the United States, residing at Chicago, in the county of Cook and State of Illinois, have invented a new and useful Improvement 5 in Blowpipe Apparatus, of which the following is a specification.

My invention relates particularly to blowpipe apparatus adapted to the use of gaso- 10 lene or other volatile oil as a fuel.

My primary object is to provide an improved carbureter having the characteristics of absolute safety, exceeding neatness and reasonable cheapness, and capable of 15 prolonged and sustained production of a mixture of unvarying quality always adapted to perfect combustion.

A further object is the provision of improved means for regulating the blowpipe- 20 flame, whereby the flame may be varied gradually or instantly from the finest needle-point to the usual brush-flame.

The invention is illustrated in its preferred embodiment in the accompanying drawings, 25 in which—

Figure 1 represents my improved blowpipe apparatus, the carbureter being shown in section; Fig. 2, a sectional view of the compound blowpipe employed; Fig. 3, an enlarged broken section taken as indicated at line 3 of Fig. 1 and illustrating a detail of a valve employed with the end piece of the blowpipe; Fig. 4, an enlarged broken section taken as indicated at line 4 of Fig. 1, showing a detail of the valve serving to regulate the admixture of air and oil vapor to insure perfect combustion; and Fig. 5, a perspective view of a clip or rest employed in connection with the handpiece of the blowpipe and 40 serving to support the same with the tip upturned when desired.

In the construction shown A represents the carbureter, and B the blowpipe.

The carbureter comprises a glass jar a of 45 substantially uniform diameter and having an open upper end closed by a metallic top a'; a nipple a² having threaded connection with the upper portion of the top a' and equipped within the vessel with a depending air-pipe a³; a pair of perforate disks or plates a⁴ a⁵ equipped, respectively, with tube-sections a⁶ a⁷, which telescope with each other; a filling 50 of absorbent material a⁸, confined between said plates, and a valve a⁹, located within the

tube a³ and equipped with a stem extending 55 upwardly through the nipple a² and provided thereabove with an adjusting-knob a¹⁰. The nipple a² is provided with a passage through which air is admitted to the tube a³ and is equipped with a laterally-extending tube a¹¹, 60 to which is attached a hose a¹², which may be connected with an air-pump, a foot-bellows, or other source of compressed-air supply. The top a' comprises a neck portion a¹³, having its lower end cemented or otherwise 65 joined to the upper end of the bottle and its upper end contracted, and a cap portion a¹⁴ of relatively small diameter, which is brazed, soldered, or otherwise joined to the upturned flange of the neck portion. Obviously the 70 two parts a¹³ a¹⁴ may be integrally formed by the use of suitable dies. The neck portion a¹³ is equipped with a removable plug a¹⁵, whereat gasolene may be introduced. The cap portion a¹⁴ is provided internally at its 75 upper portion with a depending sleeve which is internally threaded to receive a threaded portion of the nipple a². Beneath this point of connection the nipple a² has a threaded extension a¹⁶, with which the upper end of 80 the tube a³ has threaded connection. The stem of the valve a⁹ passes upwardly freely through the vertical portion of the air-admission channel in the nipple a² and extends through a closely-fitting perforation above 85 said channel, the knob a¹⁰ being screwed upon the upper end of the stem. The knob is so firmly connected with the stem that it will serve as a medium for rotating the valve in either direction. The cap portion a¹⁴ is 90 equipped with adjacent outlet-nipples a¹⁷ a¹⁸, with which are connected the rubber tubes leading to the blowpipe. A nipple a¹⁹ is also provided, and this nipple may be provided with a valve, (not shown,) enabling gas to 95 pass to any other burner. (Not shown.)

The plates a⁴ a⁵ preferably fit accurately within the jar, which usually is of circular cross-section, and the telescopic connection of the tube-sections a⁶ a⁷ enables a desirable 100 degree of compression of the absorbent material to be secured. The tube a³ is equipped near its lower end with an external collar a²⁰, between which and the plate a⁴ is confined a gasket a²¹. The lower end of the tube a³ fits within the upper end of the tube a⁶. The disk a⁵ is fitted onto the lower end of the tube a⁷, being raised slightly above the lower

end thereof, and is then soldered in place. The extreme lower end of the tube a^7 is notched or cut away, so that air can pass freely beneath the disk a^5 .

5 In manufacturing the carbureter the disks with the requisite amount of absorbent material are first introduced into the jar, and the top a^{13} is then secured in place, the joint being hermetically sealed. The nipple a^2 , 10 the tube a^3 , and the valve a^9 are then assembled, and the tube a^3 is then passed through the opening in the cap a^{14} , the washer a^{21} being first put in place, and when the nipple a^2 is screwed down the disk a^4 is forced downwardly, thereby compressing the absorbent 15 material. The resiliency of the absorbent material is sufficient to form a close joint at the gasket a^{21} . It will be seen, therefore, that the air is forced to follow a course downwardly to the bottom of the carbureter and then upwardly through the absorbent material into what may be termed the "mixture-chamber" above the plate a^4 . The tube a^3 is provided above the disk a^4 with 20 perforations a^{22} , guarded by the valve a^9 . It will be understood that the valve a^9 may be adjusted to regulate the mixture of air and oil vapor, so that correct proportions for complete combustion may be maintained at 25 all times. In practice the carbureter is charged with sufficient oil to completely saturate the absorbent material and no more. Extensive operation of the improved carbureter has demonstrated that not only has 30 economy of operation been obtained by means of the new construction, but a uniform quality of vapor can be produced and sustained during practically the whole period of operation from a given charge of oil.

35 40 In this respect the improved generator differs from generators in which free gasolene is employed, it having been demonstrated that the oil is not impoverished during the first portion of the operation of the device immediately following the charging of the carbureter. Moreover, absolute safety is attained, 45 it being possible to invert the generator during operation without the slightest detriment.

50 55 The general construction of the blowpipe B is now well understood in the art. It comprises a relatively large tube b and a relatively small tube b' , combined in the manner illustrated in Patent No. 586,066, granted to Walter Sams, July 6, 1897, and equipped with a burner b^2 of the kind shown in said patent. As shown, the burner end of the pipe b is bent at an angle, and the burner end of the pipe b' passes within the pipe b . Back 60 of the point of junction between said pipes I provide an improved valve b^3 , which is connected with the pipe b . The valve b^3 comprises a tubular casing b^4 , which passes through a perforation in the pipe b and has 65 solder connection with the walls of said per-

foration. The lower end of this casing is closed, and the upper end has screwed thereon a cap b^5 . The inner surface of the casing tapers, and the casing receives a tapered plug-valve b^6 , the stem of which passes 70 through the cap b^5 , being equipped externally with a crescent-shaped operating-handle b^7 . Encircling the stem within the casing is a spring which tends to maintain a close joint between the valve and its casing. 75 The valve is provided with a perforation b^8 and with a circumferential groove b^9 . The casing is provided within the pipe b with aligned perforations b^{10} , which register with the groove b^9 . The valve may be turned to 80 bring the perforation b^8 into registration with the perforations b^{10} . As long as gas is generated it will pass freely through the small tube b' , thereby maintaining the needle-point flame, and some gas will also pass 85 through the groove b^9 and reach the flame through the pipe b . The handle of the valve is well adapted to enable the valve to be turned by the thumb while the operator is working with the blowpipe. The valve 90 may be turned to bring the perforation b^8 gradually into registration with the perforations b^{10} , or the valve may be given an instantaneous turn, so that the size of the flame may be regulated at will without the work of 95 the operator being interrupted.

As shown, the pipe b' forms a loop with the pipe b near the bends in the pipes, and I have provided a sheet-metal clip c , adapted to be sprung into place between the pipes and to 100 serve as a rest for supporting the blowpipe when the operator desires to lay the pipe down. This clip has a curved back c' adapted to engage the pipe b' and converging limbs c^2 , whose extremities are adapted to engage 105 the pipe b . The curved back serves the purpose of enabling the angles c^3 to project somewhat beyond the outer or convex surface of the pipe b' , so that the angles virtually serve as feet for supporting the blowpipe. 110

Many features of advantage not enumerated above may be attributed to the improved carbureter, and these advantages will be at once appreciated by those skilled in the art.

Changes in details of construction within the spirit of my invention may be made. Hence no undue limitation should be understood from the foregoing detailed description.

What I regard as new, and desire to secure by Letters Patent, is—

1. In a carbureter, the combination of a receptacle, an air-pipe extending into said receptacle and equipped with means for directing a portion of the air through the liquid and provided above the liquid-level with an opening, and a valve guarding said opening and provided with external adjusting means, for the purpose set forth.

2. In a carbureter, the combination of a receptacle provided with a suitable top, a nipple connected with said top and provided with an air-passage and a laterally-extending tube connected with said passage, a tube depending from said nipple into said chamber and having outlets into the chamber located at different levels, and a valve guarding one outlet and provided with a stem projecting above said nipple, and equipped at its upper end with operating means, for the purpose set forth.

3. In a carbureter, the combination of a receptacle, an air-pipe extending into said receptacle and equipped at its lower portion with means for directing the main portion of the air through the gasoline and provided at a higher level with an opening, a nipple connected with the top of the generator and having a laterally-extending tube, a valve within said first-named tube provided with a stem journaled in said nipple and extending freely through the air-passage of the nipple, and external adjusting means connected with the upper end of said stem, for the purpose set forth.

4. In a carbureter, the combination of a vessel of substantially uniform internal diameter, a pair of perforate disks therein equipped with telescoping tubes, absorbent material between said disks, a top for said vessel, and an air-tube connected therewith and joined to and serving to depress the upper disk, for the purpose set forth.

5. In a carbureter, the combination of a receptacle, two perforate members therein having telescopic tubular connection, absorbent material confined between said members, a top for the vessel, an air-supply tube connected with said top and having a collar bearing upon the upper one of said perforate members, and an outlet connected with said top, for the purpose set forth.

6. The combination of a jar, a compressi-

ble pad of absorbent material with an extensible tubular passage through the same, a top for the jar, and a tube connected with said top and telescopically joined with the passage in said pad and having a flange bearing upon the pad, for the purpose set forth.

7. In a carbureter, the combination of a jar, a lower perforate disk supported above the bottom of the jar and equipped with an upwardly-extending tube, an upper perforate disk equipped with a downwardly-extending tube telescoping with said first-named tube, interposed absorbent material, a top for said jar provided with an outlet, an inlet-tube connected with said top and the tube of said upper disk and equipped with an external collar, and a gasket confined between said collar and said upper disk, for the purpose set forth.

8. In a carbureter, the combination of a jar of uniform internal diameter, a top cemented thereon and equipped with a removable plug and provided with an outlet-passage, an absorbent pad having a central vertical passage, and an air-inlet pipe having threaded connection with the upper central portion of said top, and having, as its only connection at the lower end, slip-joint connection with the passage in said pad whereby the tube may be removed without removal of the top, substantially as and for the purpose set forth.

9. In a carbureter, the combination of a receptacle, an air-pipe depending into said receptacle and having outlets into the receptacle located at different levels, a valve guarding one outlet and having a stem extending longitudinally of said air-pipe, and external adjusting means connected with the valve-stem, for the purpose set forth.

JOHN BERG.
